UNITED STATES PATENT OFFICE.

HENRY P. FISKE, OF WATERBURY, CONNECTICUT, ASSIGNOR TO THE AMERICAN RING COMPANY, OF SAME PLACE.

MACHINE FOR FINISHING DECORATIVE NAILS.

SPECIFICATION forming part of Letters Patent No. 398,038, dated February 19, 1889.

Application filed August 4, 1888. Serial No. 281,927. (No model.)

To all whom it may concern:

Be it known that I, HENRY P. FISKE, of Waterbury, in the county of New Haven and State of Connecticut, have invented an Improvement in Machines for Making Decorative Nails; and the following is declared to be a description of the same.

My present invention relates to a machine for making decorative nails, and the same is an improvement upon Letters Patent No. 388,126, granted to me August 21, 1888; and my invention also aims to combine with its improvements to the machine the dies and matrices and the method of cutting the blanks and forming the decorative nails such as is described in my application for Letters Patent filed June 25, 1888, Serial No. 278,122, and in my application filed June 25, 1888, Serial No. 278,123.

20 In the manufacture of decorative or ornamental nails before my invention and aforesaid patent it has been usual to form the blank for the nail-head in one machine, to make the wire nail by another machine, and 25 to join the head to the wire nail in a third machine to form the completed nail. The operations have been attended with considerable expense and loss of time.

In my present invention the blank is cut 30 and the wire nail formed and the blank is stamped to form the head and is joined to the wire nail to form the completed nail all in one machine by mechanism that coacts simultaneously, each operation cutting the blank 35 and forming the nail from a previously-cut blank.

My present invention relates to a device for guiding the vertical moving blank strip, devices for simultaneously cutting the blank 40 and forming the blank nail-head from a previously-cut blank, devices for automatically pushing the cut blank out of the matrix and for insuring its vertical fall, devices for guiding the blank as it falls and for stopping and 45 retaining the same in front of the matrix, in which the nail-head is stamped up and connected to the shank or wire, and devices for holding and securing the cutting-die and matrix, all of which mechanism or devices are 50 hereinafter more fully described.

In the drawings, Figure 1 is a plan of a por-

tion of the machine. Fig. 2 is a vertical longitudinal section of the parts in Fig. 1. Fig. 3 is an elevation of the forming-dies. Fig. 4 is an elevation of the matrix and the mechanism for guiding the blank-strip and the cut blank, Figs. 3 and 4 being in larger size. Fig. 5 is a sectional plan at the line $x-x$ of Fig. 2; and Fig. 6 is a sectional plan at $y-y$, Fig. 2, Figs. 5 and 6 being shown in larger size. Fig. 7 is a side view, and Fig. 8 a face view, of the devices for guiding the blank-strip and for covering the cut blank, Figs. 7 and 8 corresponding in size to Figs. 5 and 6.

A represents the frame-work of the machine; B, the reciprocated gate or slide-block; B', the pitman or connecting-rod; C, the matrix upon the gate B; D, the die to form the inner side of the nail-head; E, the head-block; E', the moving clamp to hold the wire; F, the cam-bar, fastened to the gate B. 2 represents the stationary tubular plug, which passes through the head-block E and supports the die D, through which tubular plug passes the wire to form the stem of the nail. 3 represents a jaw, and 4 a moving lifter-bar, and 5 a roller connected to the lifter-bar 4 and operated by the cam-bar F, the pitman or connecting-rod B being operated by a crank, the parts just named being identical with those described in my aforesaid patent, and I remark that the devices set forth in my said patent for feeding the wire along and the cutters for severing the wire into lengths and pressing up the point of the nail and a head 85 on the wire for the next nail are to be used with my present improvements; but it is not necessary to illustrate the same or further describe the parts herein.

I will now proceed to describe the present 90 improvements.

The reciprocated gate or slide-block B carries the dovetailed block C', and said block C' supports the matrix C (see Fig. 6) and the upper matrix, M. (See Fig. 5.) The die N 95 acts with the matrix M to stamp out from the strip a blank from which the nail-head is formed, and it is supported by the slotted plate 7, which plate is secured to the head-block E by bolts 8. (See Fig. 3.) This plate 100 7 is adjustable vertically by the slots in the same, and is held by the bolts 8, and on said

plate 7 there is a projecting finger, 9, whose function is hereinafter described. There is a bolt, 12, for securing the matrix C in the block C', and there is a bolt, 13, for securing the matrix M in the block C', it being possible to remove either or both of these matrices by loosening the bolts 12 or 13.

There is a vertical slotted two-part frame, a, secured by bolts to the upper face of the block C', and the parts of the frame a are held together by bolts, the slot between and within the parts of said frame being shown in Fig. 4 by dotted lines, and the strip of metal from which the blank is cut is fed vertically through the slot in the frame a, the feed being given progressively and regularly by any desired or well-known mechanism, which forms no necessary part of the present invention. The two-part frame a is cut through and a portion removed in front of the matrix M to provide for the entrance of the die N to cut the blank from the strip. There is an opening at 10 through said frame a, and a portion of the face of the frame a is cut away, and within the same there is a pivoted guide-plate, b, of the shape shown in full lines, Fig. 4, and dotted lines in Fig. 8. This guide-plate b has a depending portion, which in its normal position covers the opening in the matrix M, and there is a spring, b', upon the back of the frame a, one end of which is secured to a stud upon the back of said frame a, and the other end of said spring engages the stud 14 of the plate b and acts to keep such plate b down into the position shown in Fig. 4. This plate b is raised in the operation of the parts by the finger 9 upon the plate 7, which finger passes below the end of the plate b and through the opening 10 and raises the plate b into the position shown in Fig. 8, thus elevating said plate out of the way of the die N as said die N enters to cut the blank from the strip of metal.

The central portion of the gate or slide-block B and the central rear portion of the block C' are cut away to form a vertical opening at 11, and upon the rear portion of the block C', within the opening 11, there is a stud, c, and pivoted to said stud c is a vertical bar, d. There is a helical spring, e, placed horizontally, the ends of which spring are received in openings made in the bar d and the block B, and said spring e acts to press the vertical bar d away from the block B toward the block C'. Within the block C' there is a headed slide-rod, f, and within the matrix-block M there is a slide-block, f', the slide-rod f and the slide-block f' touching each other and being in the same axial line. Passing through the upper end of the vertical bar d there is an adjustable screw-bolt, h, Figs. 1 and 2, and there is a projecting finger-bar, i, which finger-bar is bolted to the slide-rest i' of the frame A, and the same projects from said slide-rest over the reciprocated gate B. The forward edge of said finger-bar i is adapted to engage the back end of the adjust-

able screw-bolt h, so that when the reciprocated gate B is moved backward the screw-bolt h is brought against the finger-bar i and moves the vertical bar d forward toward the block C', simultaneously therewith moving forward the slide-rod f and the slide-block f'.

The face of the matrix C has vertical guide-bars k fastened to it, and said guide-bars k are grooved on their back edges with grooves that stop at the base of the matrix-opening, the width across the opening between the vertical inner edges of the bars k being just sufficient to allow the head of the finished nail to be withdrawn or to fall out of the matrix C.

The operation of the parts is as follows, starting with the parts in the position Figs. 1 and 2: The metal blank-strip is fed downwardly through the slotted two-part frame a, its lower end covering the opening in the matrix M and the guide-plate b being down in the position Fig. 4. The reciprocated gate or slide-block B and the block C' are now moved forward by the pitman or connecting-rod B' and approach the dies D N. The finger 9 raises the plate b, and the die N cuts the blank from the strip of metal and pushes said blank into the opening in the matrix M. The face of the block f' is flat, and the face of the die N is recessed, so that the pressure squeezes the metal sufficiently to throw up a central hollow teat, such as shown in Fig. 5 of my aforesaid patent. The reciprocating gate B and block C' now move backward, the finger 9 withdrawing, and the plate b moving down and covering the opening in the matrix M, and the screw-bolt h comes against the finger-bar i, and the bar d is pushed forward and moves with it the rod f and the block f', and the blank is pushed out of the matrix M and falls through the slot in the base of the frame a and through between the guide-bars k down in front of the opening in the matrix C. The gate B and the block C' are now moved forward again by the pitman or connecting-rod B', this movement operating the cam-bar F, the roller 5, the lifter 4, and the clamp E' to hold the wire which forms the stem of the nail. The matrices C and M and the dies D and N now approach each other, and the finger 9 raises the guide-plate b, and the die N, entering, cuts the second blank from the vertically-fed strip and pushes the same into the matrix M, and simultaneously therewith the die D forces the previously-cut blank into the matrix C and forms the finished nail-head and closes the teat around the neck in the manner set forth in my aforesaid patent.

The block B now draws back and the matrix C draws away from the nail-head, and the wire forming the nail-shank is fed along through the tubular die D, as in my aforesaid patent, and the point is formed and the nail separated and falls down, and at the same time the head and neck are formed upon the end of the wire ready for receiving the next sheet-metal head, as in my said patent. As the finger 9 is withdrawn from the opening

10 in the frame *a* the spring *b'* causes the plate *b* to descend into the position shown in Fig. 4 and cover the opening in the matrix *M*, and as the gate *B* and block *C'* draw back 5 farther the bar *d*, rod *f*, and block *f'* act to push the cut blank out of the matrix *M*, so that the same can fall through the slot in the frame *a* and between the guide-bars *k* down in front of the opening in the matrix *C*. The 10 plate *b*, as the blank is pushed out of the matrix *M*, prevents the blank falling away from the position desired and insures its vertical fall through the channel provided for it, so that it stops in front of the opening 15 in the matrix *C* ready for the next forward movement to form from it the finished nail-head, and the operations just described are continuously repeated with each forward and backward movement of the reciprocated gate 20 *B*, one blank being cut out and the previously-cut blank being stamped up to shape and put upon the wire shank at the forward movement, and the blank being pushed out of the matrix *M* and falling vertically into position 25 for making the next nail-head on the backward movement.

I claim as my invention—

1. The combination, with the gate *B* and block *C'*, of a slotted frame, *a*, a pivoted 30 guide-plate, *b*, a spring, *b'*, and a finger for raising the plate *b*, substantially as and for the purposes set forth.
2. The combination, in a machine for forming decorative nails, with the head-block *E*, of 35 the slotted plate 7, the die *N*, connected therewith, and bolts 8, for securing said plate 7 adjustably to the head-block *E*, substantially as set forth.
3. The combination, in a machine for forming decorative nails, with the head-block *E*, of 40 the slotted plate 7, the die *N*, connected therewith, and bolts 8, for securing said plate 7 adjustably to the head-stock *E*, and a projecting finger, 9, secured to the slotted plate 7, 45 substantially as set forth.
4. The combination, in a machine for forming decorative nails, with the reciprocating

gate *B* and the block *C'*, of the die *N* and matrix *M*, the slide-block *f'* within the matrix *M*, the slide-rod *f* within the block *C'*, and 50 mechanism, substantially as specified, for imparting an endwise movement to the slide-block and slide-rod, whereby the blank cut by the die and matrix and struck up is pushed out of the matrix, substantially as set forth. 55

5. The combination, with the reciprocating gate *B* and dovetailed block *C'* and the matrix *M*, of a vertical bar pivoted to the block *C'*, a projecting finger for moving said vertical bar, and a block or rod moving through 60 the block *C'* and through the matrix *M*, whereby the blank is pushed out of the matrix *M*, substantially as set forth.

6. The combination, with the reciprocating gate *B* and dovetailed block *C'* and the matrix 65 *M*, of a vertical bar pivoted to the block *C'*, a projecting finger for moving said vertical bar, and a block or rod moving through the block *C'* and through the matrix *M*, whereby the blank is pushed out of the matrix *M*, and 70 a pivoted plate adapted to set across the opening in the matrix *M*, so that when the blank is pushed out of said matrix said plate insures its vertical fall, substantially as set forth.

7. The combination, with the reciprocated 75 gate *B* and the dovetailed block *C'* and the matrix *M*, of the stud *c* on the back of the block *C'*, the vertical bar *d*, pivoted to the stud *c*, the spring *e*, the adjustable screw-bolt *h*, the projecting finger-bar *i*, the slide-rod *f* 80 and slide-block *f'*, and the pivoted guide-plate *b*, substantially as and for the purposes set forth.

8. The combination, with the reciprocated gate *B* and dovetailed block *C'* and the 85 matrices *C* and *M*, of the slotted frame *a*, pivoted guide-plate *b* and spring *b'*, and the vertical guide-bars *k*, substantially as and for the purposes set forth.

Signed by me this 30th day of July, 1888.

HENRY P. FISKE.
